APPARATUS FOR CUTTING BOOK MATCH SPLINTS

Samuel E. Rahe, Springfield Gardens, N. Y.

Application October 20, 1943, Serial No. 506,941

9 Claims. (Cl. 144—50)

1

This invention relates to devices for forming match splints and relates more particularly to devices for cutting and crimping book match splints preparatory to dipping and assembling the splints into book form.

An object of the present invention is to provide a simple and effective cutting device which is capable of severing match blanks into a plurality of connected or unconnected splints.

Another object of the invention is to provide a cutting device by means of which book match splints can be cut at a higher speed than is possible with devices of the types heretofore known.

A further object of the invention is to provide a simplified cutter member having a plurality of blades that can be removed and replaced easily without completely dis-assembling the cutter member.

A still further object of the invention is to provide a device which is capable of cutting and crimping wooden book match splints without danger of splitting or buckling the match blanks.

Other objects of the invention will become apparent from the following description of a typical form of device embodying the present invention.

Devices of the type embodying the present invention are characterized by the inclusion of a hopper for receiving a stack of thin sheets of wood, hereinafter called match blanks, from which the individual blanks can be ejected one by one. Adjacent the hopper is a cutting member having a slot or passageway therethrough for receiving the match blanks as they are ejected from the hopper. Extending across or spanning the slot or passageway are a plurality of knife blades for cutting the blank along a plurality of spaced parallel lines to form the splints. Preferably, the knife blades are disposed wholly within the periphery of the cutting member and are so arranged that when the match blank is passed into the slot it is only partially severed.

The cutting member is rotatably mounted so that the match blanks are introduced into the slot of the cutting member alternately from opposite ends thereof. As a result, a previously inserted and partially severed match blank is ejected backwardly from the slot by the next succeeding match blank without completely severing the splints.

The splints connected by the web may then be received in a suitable crimping member which separates or spreads the free ends of the splints and delivers the splints to a dipping machine where they may be dipped and later delivered to a machine for assembling the blanks into book form.

2

If desired, the cutting member can be arranged so that it is not rotated and the match blanks, therefore, will be pushed completely through the cutting member with the result that the splints are completely separated from each other.

More particularly, the cutting member suitably may have end plates which are provided with stub shafts for supporting the cutting member rotatably and is provided with a plurality of spacer members between which the knife blades are supported. The whole assembly may be clamped by means of bolts or the like so that the knife blades can be inserted or removed simply by loosening the assembly so that the blades will drop out of the device, thereby permitting their ready replacement when they become dull.

The device may be arranged to include cutting members on opposite sides of the hopper so that a match blank is severed partially or completely upon each stroke of the mechanism that is utilized to push the match blanks from the hopper. Such an arrangement has the advantage of permitting substantially twice as many match blanks to be severed in a given period of time as with the devices of the type known heretofore.

The device embodying the present invention is particularly adapted to the formation of wooden book match splints for the reason that the slot in the cutting member has a tendency to confine and prevent buckling or breaking of the thin match blanks.

For a better understanding of the present invention, reference may be had to the accompanying drawing, in which:

35 Figure 1 is a plan view of a typical form of device embodying the present invention;

Figure 2 is a view in section taken on line 2—2 of Figure 1;

Figure 3 is a view in side elevation of the device;

Figure 4 is a view in cross-section taken on line 4—4 of Figure 1;

Figure 5 is a view in elevation of a typical form of cutting member embodying the present invention; and

Figure 6 is a view in cross-section of a cutting member, showing a modified type of cutting element.

The form of the invention chosen to illustrate 50 the invention consists of a frame 10 having parallel side members 11 and 12 housing the operating mechanism of the device and supporting the various cooperating elements thereof.

Substantially midway of the side members 11 and 12 is mounted an elongated rectangular hop-

per 13 which is adapted to receive a stack of match blanks B. The match blanks B may vary in size, as desired. For example, the blanks B may be of a size suitable for only one conventional size book match package or they may be of a length sufficient to form the splints for ten or more book match packages.

The hopper 13 is provided with a bottom plate 14 forming the upper side or top of a chamber 15 which may be subjected to a reduced pressure by means of a vacuum pump (not shown) connected to the coupling 16 in the bottom thereof. The bottom plate 14 is provided with a plurality of perforations 14a through which suction may be exerted on the bottom blank B of the stack, to draw it against the bottom of the hopper.

The side walls 17 and 18 of the hopper may be provided with slots 17a and 18a through which the match blanks B are ejected by means of a pusher plate or ejector 19. The pusher plate 19 is adapted to slide back and forth across the bottom 14 so that upon movement to the right, it will eject a blank B to the right, and upon movement to the left, it will eject a blank B to the left. The pusher plate 19 is actuated by means of a yoke member 20 having a slot 21 in each of its arms 22 and 23 which receive the reduced extensions 24 on opposite ends of the pusher plate 19. The extensions 24 are received in slots 11a and 12a in the frame members 11 and 12, respectively, which guide and prevent chattering and wobbling of the pusher plate 19.

The chamber 15 is supported upon arms 25 projecting from a cross-bar 26 connected to the side members 11 and 12 so that the ends of the chamber 15 are spaced from the side members 11 and 12 a sufficient distance to permit the arms 22 and 23 of the yoke to pass between the ends of the chamber 15 and the side members 11 and 12.

Upon opposite sides of the hopper 13 are disposed cutting members 27 and 28 which are identical in construction. The cutting member 27, as illustrated in Figures 1, 2 and 5, consists of a pair of disk-like end plates 29 and 30 having the stub shafts 31 and 32 projecting therefrom that are received rotatably in the journals 33 and 34 in the side members 11 and 12, respectively.

A plurality of pairs of spacer members 35 are mounted between the end plates 29 and 30. The number of pairs of spacer members 35 corresponds to the number of match splints that are to be formed in the blank. As shown particularly in Figure 2, the spacer members 35 may consist of substantially semi-circular plates having their inner edges 35a spaced apart to provide a slot 36 for receiving the match blank B. While the spacer elements 35 are illustrated as semi-circular in shape, it will be understood that they do not have to be of this shape, nor do the end plates 29 and 30 have to be disk-like or circular. They may take the form of polygonal figures, if desired, or other non-circular shapes so long as the axis of rotation of the cutter member 27 is in the plane of the slot 36 and the slot 36 is in alignment with the slot 17a in the hopper.

As shown particularly in Figure 2, the cutting elements or blades 37 which are mounted between the spacer elements 35 may be similar to conventional flexible double-edged razor blades, that is, they have cutting edges facing in opposite directions so that they are capable of severing or partially severing the match blanks B, regardless of the direction that the blank B is forced into the slot 36. The blades 37 are clamped between the spacer members 35 by means of a plurality of

bolts 38 which pass through the end plates 29, 30 and the spacer members 35. Thus, upon loosening of the bolts 38, one or more of the blades 37 can be removed and replaced, if necessary.

The blades 37 can be of shapes other than rectangular, if desired. Thus, as shown in Figure 6, the blades 39 are sharp-edged disks of smaller diameter than the end plates 29 and 30. Two of the blades 39 may be mounted between the spacing members 35 in spaced relation. Similarly, single-edged blades or triangular blades may be used, if desired.

Referring now to Figure 2, it will be seen that when the pusher plate 19 has ejected a match blank B to the left from the hopper 13, the blank B will be pushed partially through the slot 36 so that the blank B is received wholly within the periphery of the cutting member 28. The blank B, in this position, is only partially severed into splints that are connected by a continuous web portion of the blank.

Upon movement of the pusher member 19 to the right, a match blank is ejected through the right-hand slot 18a into the cutter member 27 which, as illustrated, already contains a partially severed match blank B. However, the unsevered or web portion of the match blank B in this case is directed to the right for the reason that the cutter 27 has been rotated through one-half a revolution since it last received a match blank B. The incoming match blank B, therefore, will push the blank B that is within the cutter 27, out of the cutter 27, without completing severance of the blank B within the cutter 27. Thus, the action of the cutting members 27 and 28 is to receive a blank from one side, then rotate and receive a blank from the opposite side, which action causes the ejection of the first severed match blank. Of course, if the cutting members 27 and 28 are not rotated between feeding strokes of the pusher member 19, the match blanks B will be pushed completely through the cutting member and the blanks B will be severed into individual splints.

In order to clamp and separate the splints in the partially severed blank, crimping devices 40 and 41 are mounted on opposite sides of the cutter members 27 and 28. Each of these crimping members may consist of a bottom plate member 42 having grooves 43 and 44 for receiving the rails 45 and 46, respectively, on the inner surfaces of the members 11 and 12, respectively, so that the plate can slide bodily toward and from the cutting members 27 or 28. Upon the upper surface of the plate member 42 is a crimping element 47 having a plurality of alternate flat top teeth 48 and flat bottom recesses 49. As best shown in Figure 2, the upper surfaces of the teeth 48 are inclined at an acute angle to the horizontal and to the bottoms of the recesses 49. The bottoms of the recesses 49 also are inclined at an acute angle to the horizontal. The recesses 49 and teeth 48, respectively, are complementary to the teeth 50 and recesses 51 of an upper crimping element 52 which is movable toward and away from the lower crimping element 47. The upper crimping element 52 is provided with end lugs 53 and 54 which are slidable upon bolts 55 and 56 that are fixed to the plate member 42. The upper crimping element 52 is raised by means of springs 57 interposed between the lugs 53 and 54 and the plate member 42.

The spacing between the crimping elements 47 and 52 normally is such that the match blank B ejected from one of the cutters 27 or 28 can

pass freely between these elements, as illustrated at the left-hand end of Figure 2.

When the crimping elements 47 and 52 are forced together, the individual splints on the partially severed blank B are forced apart in angular relationship, as illustrated at the right-hand end of Figure 2.

When the blanks B are crimped, as described above, they may be transferred to any desired type of dipping machine 58 for dipping the splints and then transferred to a conventional assembling and stapling device (not shown).

All of the operations described generally above must be conducted in a timed sequence so that the cutters 28 and 29 will remain stationary while receiving the match blanks B.

The crimping members 40 and 41 must travel along the rails 45 and 46, crimp the match blanks B, insert them in the clips 59 on the dipping device, release the crimped blanks and return to adjacent the respective cutting elements 27 and 28 in time to receive the next blank B ejected from the cutting device. Also, the cutting devices must be rotated through one-half a revolution between the time that a match blank B is ejected therefrom into the crimpler 40 or 41 and the time another match blank is delivered to the cutter 27 or 28 from the hopper 13.

The mechanism for producing these various movements will now be described.

As shown particularly in Figures 1 and 3, a main drive shaft 60 is journaled in the side members 11 and 12 of the frame 10 and may be driven in any suitable way. The shaft 60 is provided with a heart-shaped cam 61 which is received between the rollers 62 and 63 that are mounted on a cross-bar 64 connected to the yoke 20. The yoke 20 is pivotally mounted on a shaft 65 adjacent the bottom of the frame 10. Thus, for every revolution of the shaft 60, the yoke 20 is oscillated back and forth and the pusher member 19 travels across the bottom 14 of the hopper 13 in one direction and returns, thereby ejecting two blanks B in opposite directions.

In order to rotate the cutting members 27 and 28, the ends of the shafts 31 thereof are provided with gears 66 which are connected thereto by overrunning clutches 67. As shown in Figure 3, the overrunning clutch 67 on the cutter 27 is arranged to rotate the cutter 27 in a clockwise direction only. The overrunning clutch 67 on the cutter 28 is arranged to rotate the cutter 28 in a counter-clockwise direction, only.

The gear 66 on the cutter 27 and the gear 68 on the cutter 28 are rotated by means of the racks 69 and 70. The racks 69 and 70 are slidably mounted on guideways 71 and 72 on the frame member 12 and are reciprocated by means of the bell crank levers 73 and 74 which are urged against the cams 75 and 76 that are mounted on the shaft 60 by means of the springs 75a and 76a. The shapes of the cams 75 and 76 are such that a complete reciprocation of the racks 69 and 70 is obtained in something less than one-half a revolution of the shaft 60. The cams 75 and 76 are so timed that the racks 69 and 70 do not move until a blank B has been ejected from the cutter 27 or 28 driven by the corresponding rack.

The ends of the racks 69 and 70 are connected to the crimping members 40 and 41, respectively, by means of the links 77 and 78 (Figures 1 and 3). Thus, when the rack 69 is moved to the right by means of the cam 76, the crimpler 40 is also moved to the right, while the gear 66 idles with respect to the cutter 27. Upon return movement of the

rack 69 to the left, the overrunning clutch 67 is actuated and the cutter 27 is rotated clockwise through one-half a revolution as the crimpler 40 returns to a position adjacent the cutter 27.

Thereafter, the cam 76 causes the rack to dwell for a sufficient length of time to permit another blank B to be introduced into the cutting member 27.

The cutting member 28 and the crimpler 41 are actuated in a similar manner, but alternately with the movement of the crimpler 40 and the cutter 27, inasmuch as the match blanks B are introduced into the cutters 27 and 28 alternately.

In order to actuate the crimping mechanisms 40 and 41 to first grip the blanks B, thereafter crimp the blanks and then release the blanks after they have been forced into the clips 59, a separate cam mechanism is provided. The cam mechanism, best shown in Figures 2 and 4, may consist of aligned cam plates 80 and 81 which are mounted upon pairs of rods 82 and 83 that are slidably mounted in bosses 84 and 85 on the frame members 11 and 12, respectively. The lower ends of the rods 82 and 83 are connected by means of a cross-bar 86 which passes through the slots 87 and 88 in the frame members 11 and 12. The cam plates 80 and 81 are engageable with the ends of the upper crimping member 52 and are normally spaced from the crimping member 52 when the match blank B is being pushed into the crimping member, as illustrated at the left-hand end of Figure 2.

As soon as the match blank B is received in the crimping member 41, for example, the cam plates 80 and 81 are moved downwardly to cause the crimping elements 47 and 52 to grip the match blank B. This downward movement of the cam plates 80 and 81 is accomplished by means of the cam disks 89 which are mounted upon a shaft 90 journaled in the side members 11 and 12. The cam members 89, as shown in Figure 2, are provided with spiral cam slots 91 which receive the pins 92 that project laterally from the lugs 93 on the bottom of the cross-bar 86. The cam disks 89 are connected by means of a link 94 or 95 to suitable cam disks 96 carried by the shaft 60. The cam disks 96 are so designed that they rock the cam disks 89 to move the cam plates 80 and 81 downwardly, immediately after the crimping members receive the partially severed blanks B and before the gripping members 40 or 41 begin to move away from the cutter 27 or 28.

The cam plates 80 and 81 are provided with downwardly inclined lower cam surfaces 80a or 81a, so that as the crimpler 41, for example, travels to the left, the crimping elements 47 and 52 are forced together to crimp the match blank. When the crimping element 41 has reached the end of its travel towards the left and the web of the blank B is received in a clip 59, the cam disk 89 is rocked by the cam 96 to move the cam plates 80 and 81 upwardly and thereby permit the crimping elements 47 and 52 to separate and release the crimped blank B. The crimpler 41 then is returned to its right-hand position and the dipping device 58 moves another clip 59 into position to receive the next blank.

From the foregoing description, it will be apparent that I have provided a device by means of which match blanks B can be severed, crimped and transferred at a high rate of speed.

The device has been described as showing its use with two sets of cutting and crimping members, but only one cutter and crimpler may be used, if desired.

The device has the advantage that each of the match blanks B is guided in its movement, is retained against twisting and bending during cutting and transfer and thereby is prevented from being damaged.

It will be understood from the foregoing that the device is susceptible to considerable modification, particularly in its size and in the specific mechanism for operating and timing the various elements thereof. Therefore, the form of the invention described above should be considered as illustrative and not as limiting the scope of the following claims.

I claim:

1. A device for forming book match splints comprising a hopper for receiving a stack of book match blanks, means for ejecting a blank from said hopper, a cutting member adjacent the hopper having a slot therethrough for receiving said blank and a plurality of spaced apart cutting elements having oppositely directed cutting edges spanning said slot for engaging and cutting said blank into a plurality of connected strips, and means for rotating said cutting member intermittently through half a revolution in timed relation to said ejecting means to receive blanks alternately in opposite ends of said slot.

2. A device for forming book match splints comprising a hopper having a bottom for supporting a stack of match blanks, a cutting member adjacent to said hopper having a plurality of spaced apart cutting elements having oppositely directed cutting edges extending perpendicular to the plane of said bottom, means supporting said cutting member for rotation, means for pushing a blank from said hopper into engagement with and partially through said cutting elements to sever said blank partially, and means for rotating said cutting member through a half revolution after said blank has been pushed from said hopper into engagement with said cutting elements, whereby the next blank pushed from said hopper will push the partially severed blank out of said cutting member.

3. A device for forming book match splints comprising a hopper having a bottom for supporting a stack of match blanks, a cutting member adjacent to said hopper having a plurality of spaced apart cutting elements having oppositely directed cutting edges extending perpendicular to the plane of said bottom, means supporting said cutting member for rotation, means for pushing a blank from said hopper into engagement with and partially through said cutting elements to sever said blank partially, means on said cutting member for guiding said blank into said cutting elements, and means for rotating said cutting member through a half revolution after said blank has been pushed from said hopper into engagement with said cutting elements, whereby the next blank pushed from said hopper will push the partially severed blank out of said cutting member.

4. A device for forming book match splints comprising a hopper having a bottom for supporting a stack of book match blanks, a substantially cylindrical cutting member adjacent the hopper having a diametrical slot therethrough, a plurality of spaced apart knives having oppositely directed cutting edges spanning said slot, means for ejecting a blank from adjacent the bottom of said hopper and pushing it into said slot and against and partially through said knives to sever said blank into a plurality of connected splints, and means for rotating said cutting mem-

ber intermittently through half a revolution in timed relation to the operation of said ejecting means to receive blanks alternately from opposite sides.

5. A device for forming book match splints comprising a hopper having a bottom for supporting a stack of book match blanks, a cutting member adjacent the hopper having a slot therethrough a plurality of spaced apart knives spanning said slot and having oppositely facing cutting edges disposed within the periphery of said cutting member, means for ejecting a blank from adjacent the bottom of said hopper and pushing it into said slot and against and partially through said knives to sever said blank into a plurality of connected splints, and means for rotating said cutting member intermittently through half a revolution in timed relation to the operation of said ejecting means to receive blanks alternately in opposite ends of said slot.

6. A device for forming book match splints comprising a hopper having a bottom for supporting a stack of book match blanks, suction means in the bottom of said hopper for positioning a blank in contact with said bottom, a cutting member adjacent the hopper having a slot therethrough, a plurality of spaced apart knives having oppositely directed cutting edges spanning said slot, means for ejecting a blank from adjacent the bottom of said hopper and pushing it into said slot and against and partially through said knives to sever said blank into a plurality of connected splints, and means for rotating said cutting member intermittently through half a revolution in timed relation to the operation of said ejecting means to receive blanks alternately in opposite ends of said slot.

7. A device for cutting book match blanks comprising a hopper having a bottom for supporting a stack of book match blanks, cutting members rotatably mounted in opposite sides of said hopper for receiving said blanks alternately, each of said cutting members having a slot therethrough, a plurality of spaced apart knives spanning said slot, and having oppositely directed cutting edges, a pushing member reciprocable across said bottom to eject a blank from said hopper in each direction of movement to push the ejected blank against said knives to sever said blank partially only into a series of connected splints and means for rotating said cutting members intermittently through half a revolution in timed relation to the movement of said pushing member to receive the blanks from opposite sides.

8. A device for forming book match splints comprising a hopper having a bottom for supporting a stack of match blanks, a cutting member adjacent to said hopper having a plurality of spaced apart cutting elements having oppositely directed cutting edges extending at substantially a right angle to the plane of said bottom, means supporting said cutting member for rotation, means for pushing a blank from said hopper into engagement with and partially through said knives to sever said blank partially to form connected splints, and means for rotating said cutting member through a half revolution in timed relation to the operation of said ejecting means, whereby the next blank pushed from said hopper will push the partially severed blank out of said cutting member.

9. A device for forming match splints comprising a hopper having a bottom for supporting a stack of match blanks, a cutting member ad-

jacent to said hopper having a plurality of spaced apart cutting elements having oppositely directed cutting edges extending at substantially a right angle to the plane of said bottom, means supporting said cutting member for rotation, an ejector member reciprocable across the bottom of said hopper to push blanks from said hopper successively into engagement with and partially through said knives to sever each blank partially into a series of connected splints, and means for reciprocating said ejector member.
